UNITED STATES PATENT OFFICE.

JAMES DAVIS, OF LONG ISLAND CITY, NEW YORK.

IMPROVEMENT IN WHEELS FOR VEHICLES.

Specification forming part of Letters Patent No. 124,554, dated March 12, 1872; antedated March 9, 1872.

To all whom it may concern:

Be it known that I, JAMES DAVIS, of Long Island City, in the county of Queens and State of New York, have invented a new and Improved Wheel; and I do hereby declare that the following is a full, clear, and exact description thereof, reference being had to the accompanying drawing forming a part of this specification.

This invention consists in a novel construction of the hub whereby the spokes are very firmly secured within it, and it may be adjusted to clamp and tighten them after shrinkage, and convenient provision is made for the insertion of a new spoke should one be broken. It also consists in a hollow felly of novel construction, having a concave periphery on which the tire is shrunk, and thereby secured without the use of bolts or rivets, the holes for the reception of which considerably weaken the tire.

In the accompanying drawing, Figure 1 is a face view of a wheel made according to my invention. Fig. 2 is an axial section of the same. Fig. 3 is an outside view of the hub alone. Fig. 4 is a view of the body of the hub alone; Fig. 5, a facial section of one of the fellies. Fig. 6 is a top view of portions of two, showing the manner in which they are fitted together. Fig. 7 is an end view of the hub with its cap removed, and Fig. 8 is an inside view of the cap.

Similar letters of reference indicate corresponding parts in all the figures.

A is the main portion or body of the hub, on the forward or outer portion of which there is formed a sleeve, B, on whose exterior are spirally arranged lugs or broken screw-threads *a a*, with spaces between them to permit the passage of lugs in the cap C. The rear or inner portion *c* of said sleeve is somewhat larger than the rest, and in the adjacent edge of the said body A are two series of recesses, each alternate recess *d d* being of a size to receive two-thirds of one of the spokes D D, and the intermediate recesses *e e* being of a size to receive one-third of the other spokes. E is the axle-box, which fits snugly within the body A of the hub, and has formed on the exterior of its rear portion two ribs, *b b*, that fit in grooves in the rear end of the said body A, and thereby lock it and the axle-box so as to turn together; and if necessary they may be locked longitudi-

nally by a set-screw screwing through the former and impinging against the latter. F is a collar that fits so as to be capable of sliding on the portion *c* of the sleeve C, close to, but not so as to be in contact with, the body A. This collar has formed in its inner edge two series of recesses. Each recess of one series, *f f*, is of a size to receive one-third of a spoke, and when the collar is in place come opposite one of the recesses *d d* in the edge of the body A, and with it receives one spoke; and each of the other series *g g* is of a size to receive two-thirds of a spoke, and comes opposite one of the recesses *e e*, and with it receives the end of a spoke. By thus arranging the recesses the spokes have a zig-zag appearance, alternate spokes inclining the same way, thereby bracing the wheel laterally. The cap or outside section C of the hub has formed in its interior a flange, *h*, by which it is centered on the end of the axle-box E, and in rear of this flange are two lugs, *i i*, that, as the said cap or section is fitted on the sleeve C, pass between the spiral lugs *a a* therein, and, as it is turned or screwed on, work behind said lugs and draw the cap against the collar or middle section E, thereby crowding it against the spokes and securing it in place. The cap, after having been screwed up, may be secured by a set-screw screwing through and bearing against the sleeve C. G G are the fellies of the wheel, which are of hollow construction, and open at their peripheries, as shown in Figs. 2, 5, and 6, and have a tongue, *m*, on one end, and a groove, *n*, in the other which, when the fellies are secured together, fit into one another and form a very secure joint. They have spoke-sockets *jj* formed in them of the form shown in Fig. 5, and from these sockets there extend to the periphery ribs *k k*, the edges of which are concave, and help to support the tire H. Between the said sockets are ribs *l l*, whose edges are also concave and help to support the tire. The said tire H is of concave form in its transverse section, and is shrunk over the concave ribs and ends of the fellies which form a concave periphery. By means of the described construction of the hub the cap C can be screwed up to tighten the collar on the spokes after shrinkage, and as the nut bears against the collar F instead of against the spokes, the latter are not torn or otherwise marred by

operation. Should one of the spokes be broken a new one can be inserted in its place without taking the wheel to pieces, by simply loosening or removing the cap and collar, inserting a spoke and replacing the nut and collar. By making the fellies hollow they are made very light, and by fitting them together by means of tongues and grooves, a very strong wheel is obtained. The tire, if very heavy, must be bent before being secured to the wheel; but if light may simply be shrunk on, and when thus secured is very firm, and is not weakened by any bolt-holes penetrating it.

What I claim as my invention, and desire to secure by Letters Patent, is—

1. The hub, composed of the body A, recessed at its edge, the collar F, similarly recessed, and the axle-box E, provided with spiral lugs or broken screw-threads *a a*, cap C, provided with lugs *i i*, all combined substantially as and for the purpose herein set forth.

2. The hollow iron fellies fitted together with grooves and tongues, and having concave peripheries, over which the tire is shrunk, substantially as and for the purpose herein described.

JAMES DAVIS.
